UNITED STATES PATENT OFFICE.

WILLIAM A. HENRY, OF GALESBURG, ILLINOIS.

TOASTER.

1,078,566.

Specification of Letters Patent.

Patented Oct. 31, 1913.

Application filed February 7, 1912. Serial No. 378,558.

To all whom it may concern:

Be it known that I, WILLIAM A. HENRY, a citizen of the United States, residing at Galesburg, in the county of Knox and State 5 of Illinois, have invented new and useful Improvements in Toasters, of which the following is a specification.

An object of the invention is to provide a toaster for toasting food, such as bread 10 and the like.

The invention embodies, among other features, an upper frame and a lower frame mounted to swing on the upper frame, supporting members mounted on the lower 15 frame for retaining the same in place relatively to the flame of the stove when the device is mounted upon a stove, a handle extended from the upper frame and means for retaining the lower frame in locked engagement with the upper frame.

In the further disclosure of the invention, reference is to be had to the accompanying drawings, constituting a part of this specification, in which similar characters of reference denote corresponding parts in all the 25 views, and in which—

Figure 1 is a perspective view, showing the device in closed position. Fig. 2 is a side elevation, showing the device in open 20 position. Fig. 3 is an end view. Fig. 4 is a vertical sectional view taken on the line 4—4 in Fig. 1, looking in the direction of the arrow. Fig. 5 is a fragmentary enlarged 25 perspective view, showing the manner of forming one of the hinges connecting the upper and lower frames.

Referring more particularly to the views, use is made of an upper frame 10 and a lower frame 11 mounted to swing on the 30 upper frame 10, the mentioned upper and lower frames being preferably formed of wire and provided with a series of relatively spaced cross bars 12.

A handle 13 is formed by twisting a portion 45 of an integral piece of wire, a wooden grip 14 being provided to inclose a part of the twisted portion, the ends of the said piece of wire being then extended forwardly and rigidly connected to the upper frame 10 50 at the rear end thereof and extended across the frame to form additional cross bars 15, the said ends being then bent around the front end of the upper frame 10 and extending downwardly to encircle the front end of 55 the lower frame 11, thus forming hinges 16 upon which the lower frame 11 is mounted

to swing. The upper frame 10 consists primarily of an integral piece of wire 17, bent in a rectangular shape, the said piece of material at the corners of the frame being twisted and extended upwardly to form 60 supporting members 18, the cross bars 12 and cross bars 15 being secured to the wire 17 as mentioned heretofore, with the handle 13 extended rearwardly from the wire 17 65 after the same has been bent to form the upper frame 10.

The lower frame 11 is made similar to the upper frame 10 and consists of an integral piece of wire 19 bent in a rectangular shape 70 with the said wire at the corners of the frame twisted and extended downwardly to form supporting members 20, the cross bars 12 of the lower frame being arranged to have the ends thereof engage the wire 19 as 75 will be readily understood, with the extremities of the cross bars 15, when bent around the wire 17 and then extended downwardly to engage the wire 19 and form the hinges 16, as mentioned heretofore, adapted 80 to retain the front ends of the upper and lower frames 10 and 11 in spaced relation. A plurality of the cross bars 12 of the lower frame 11 after being curved around the front side of the lower frame, have the 85 ends thereof extended downwardly to form stop members 21 to limit the swinging movement of the lower frame 11 when the same moves into open position as shown in Fig. 2.

An integral piece of wire 22 has the ends 90 thereof bent to loosely encircle the rear side of the upper frame 10 and the said piece of wire is then extended downwardly and bent around the rear side of the lower frame 11 to form a locking member 23, the mentioned 95 locking member being adapted to retain the free end of the lower frame 11 in locked engagement with the rear end of the upper frame 10.

In the use of my device, the handle 13 is 100 grasped by the grip 14 and the device is turned over so that the supporting members 18 of the upper frame 10 will repose upon the table, after which the locking member 23 is swung into open position and 105 the lower frame 11 can then be swung upwardly, the stop members 21 being adapted to engage the front end of the upper frame 10 and limit the upward swinging movement of the lower frame 11, while at the 110 same time retaining the lower frame in open position. The toast or other food to be

toasted or broiled is now placed upon the inner side of the upper frame, after which the lower frame is swung into closed position and the locking member 23 is then 5 swung to lock the upper and lower frames. The device is then placed over the flame on the stove and will be held in spaced relation thereto by the supporting members 18 of the upper frame, it being understood 10 that the device is now in its reversed position. When that side of the food which is nearest to the flame has been properly toasted, the grip 14 is grasped and the device is reversed so that the supporting members 15 20 of the lower frame 11 will repose upon the top of the stove and retain the lower frame, also the food, in spaced relation to the flame of the stove and the side of the food nearest the fire, is subjected to the action 20 of the flame to toast the food. When this has been completed, the device is removed from the stove and the locking member 23 is then swung rearwardly to disengage the same from the lower frame 11, thus 25 causing the lower frame to gravitationally swing downwardly and the toasted food will then fall from between the upper and lower frames onto the table.

It will thus be seen that the device is 30 initially used in reversed position and when the food has been properly toasted or broiled on one side, the said device is reversed and mounted on the stove in its final position before removing the food therefrom, the opposite side of the food being 35 now toasted or broiled, after which by simply releasing the locking member 23 from the lower frame, the lower frame will swing downward, thus causing the food to become 40 disengaged from the device and fall onto the table, it being well known that an operator oftentimes receives severe burns when removing the toast from the toasting devices now generally used, whereas in my device the 45 final operation is simply to release the locking member and the food will then gravitationally fall from between the frames, thus

obviating the necessity of the operator touching the food after the same has once been placed between the frames. 50

The ends of the cross bars 12 can be rigidly secured to the upper and lower frames by bending the wires of which the frames are constructed to form notches 24 into which the ends of the cross bars are 55 received, the ends being then coiled around the cross bars to secure the same in the notches.

I claim:—

As a new article of manufacture, a toaster 60 comprising an upper frame formed of an integral piece of wire, the said piece of wire at the corners of the frame being bent to form supporting members, cross bars carried on the said frame, a lower frame 65 formed of a second piece of wire, the said second piece of wire being bent at the corners to form supporting members, cross bars carried on the lower frame, a handle formed of a third piece of wire connected to the 70 upper frame, with the forward ends of the said third piece of wire bent to encircle the lower frame formed of the second piece of wire, to permit of swinging the lower frame relatively to the said upper frame, a 75 locking member formed of a single piece of wire and mounted to swing on the upper frame, with the medial portion of the locking member forming an apex and adapted to engage the lower frame adjacent the end 80 of the handle, and stop members formed by projecting a plurality of the cross bars of the lower frame beyond the front end of the lower frame, the said stop members projecting downwardly and adapted to be engaged 85 by the upper frame when the same is swung into open position, to limit the open swinging movement of the upper frame.

In testimony whereof I affix my signature in presence of two witnesses.

WILLIAM A. HENRY.

Witnesses:

Mrs. WM. HENRY,
GLADYS E. HENRY.
